UNITED STATES PATENT OFFICE.

EDWIN W. CLARK, OF CHICAGO, ILLINOIS.

PUMP-CYLINDER.

1,170,737.

Specification of Letters Patent.

Patented Feb. 8, 1916.

Application filed October 21, 1914. Serial No. 867,712.

To all whom it may concern:

Be it known that I, EDWIN W. CLARK, a citizen of the United States, residing at Chicago, in the county of Cook and State of Illinois, have invented a certain new and useful Improvement in Pump-Cylinders, of which the following is a specification.

My invention relates to pump cylinders, more particularly of the type employed in 10 deep wells.

It is well known to those conversant with this art that it is frequently desirable to remove pump cylinders from the well casings in which they are placed. Theoretically 15 this is a simple matter, but as a practical matter it is usually impossible to do so after the pump has been in operation for a short time. The difficulty is that as soon as the pump is put into operation, sand, lime 20 or other sedimentary material immediately begins to fill in around the outside of the cylinder, between the cylinder and the casing, and it is a peculiar fact, but a well known one, that this sedimentary material 25 instead of being loose and granular like sand, becomes in effect a solid piece of stone, and effectually prevents any movement whatever of the cylinder in the casing. The result is, that although the commercial pump 30 cylinders are theoretically removable, as a matter of fact they become quite immovable after a short space of time, usually after two or three days, the time depending upon the amount of impurities in the water, etc.

35 The object of my invention is to provide means for preventing the deposition of any substance or its collection between the well casing and the cylinder.

I accomplish my object by the construction illustrated in the accompanying drawings, in which—

Figure 1 is a side elevation, chiefly in central longitudinal section showing a cylinder embodying my invention in position in 45 a well casing. Fig. 2 is a central vertical section of the parts at the upper end of the cylinder, the figure showing the rubber packer expanded into contact with the well casing. The plane of section is indicated by 50 the line 2—2, Fig. 3. Fig. 3 is similar to Fig. 2, but shows the packer contracted. Fig. 4 is a plan section on the line 4, 4 Fig. 2. Fig. 5 is a plan section on the line 5, 5 Fig. 1. Fig. 6 is a perspective view of 55 a suitable form of seating tool.

Similar numerals refer to similar parts throughout the several views.

Referring to the drawings, 1 represents the well casing which forms the sides of the well. The pump cylinder 2 is tubular in 60 form and is of a diameter somewhat less than the diameter of the well casing, there being an annular space 3 formed between the cylinder and the casing. At the lower end the cylinder terminates in a foot 4, the 65 design of which is immaterial so long as it is open at the bottom for admitting water, and is adapted to be operated by a seating tool. For the purpose of illustration I have shown in Fig. 5, and at the bottom of Fig. 70 1 a configuration suitable for coöperating with the particular form of seating tool shown in Fig. 6. In the form selected for illustration said seating tool consists of a head 6 formed at the lower end of a rod 7, 75 the said head being oblong and adapted to engage the horizontal internal flange 8 in the foot. Said flange has notches 9 through which the head of the seating tool may be lowered, and the vertical ribs 10 beneath 80 said flange prevent the seating tool from being rotated too far, the action being illustrated in dotted lines Fig. 5. The foot is screwed or otherwise fastened to the lower end of the cylinder 2, it being usual to pin 85 the parts together or otherwise prevent the foot from being unscrewed by the seating tool.

Ordinarily the foot 4 will be internally tapered for receiving and supporting the 90 foot valve, which need not be described in detail as it is not directly concerned in my present invention, it being sufficient to say that said valve consists of a cage 11 surmounting a valve seat 12, the latter coöperating 95 with a vertically movable check valve 13.

Above the foot valve is a piston, the form of which is immaterial as regards my present invention. In the form shown said piston 100 consists of a plunger 14, the bottom of which is internally threaded for engaging the threaded boss 15 located at the top of the foot valve in the ordinary manner. Said plunger is surmounted by a cage 17 and provided with a vertically movable valve 18. These parts are operated by a pump rod 19 in the usual manner.

I will now describe the parts more particularly concerned with my invention—to wit, 110

the parts whereby sediment is prevented from collecting between the cylinder and the casing.

Secured to the upper end of the pump cylinder 2 is an external annular flange 21 as shown at the upper end of Figs. 2 and 3. By preference this flange is integral with the cylinder and is produced by the so-called "spinning" process. The outer diameter of this flange is almost but not quite equal to the inner diameter of the well casing, the flange being small enough to permit it to pass freely up through the well casing when the cylinder is to be withdrawn. This flange serves as a top retainer for the annular packer 22 which consists of rubber or similar resilient substance. Said flange flares outward and upward so that its outer surfaces produce a wedging action to crowd the material of the packer outward when the latter is pressed upward from beneath.

The upper end of the pump cylinder is externally threaded and is encircled by a spring dog which consists, in the main, of a sleeve 24 with springs 25 thereon. Said sleeve is internally threaded to coöperate with the external threaded portion of the cylinder, the result being that by producing relative rotation between the sleeve and the cylinder, the cylinder will be raised or lowered relatively to the sleeve. By preference said springs are arranged longitudinally and are protected at the upper and lower ends by collars 26 and 27 respectively. Said springs are rigidly fastened at the one end to the sleeve 24 by rivets 29 or other suitable means. The springs bow outwardly sufficiently to press with considerable force against the internal surface of the well casing, the purpose being to create enough friction to hold the spring dog against rotation when the cylinder is rotated. In order to reduce the friction between the top of the collar 27 and the base of the rubber packer 22 it is desirable to interpose a loose anti-friction ring 30.

The operation is as follows:—Let it be assumed that the well casing is in place and that it is desired to lower the pump cylinder and associated parts into place. The spring dog is backed off (that is, lowered on the cylinder) far enough to permit the diameter of the rubber packer 22 to contract to normal, as shown in Fig. 3. In this condition the packer is of small enough diameter to permit it to be freely lowered in the well casing. When the dog, packer and cylinder have been brought to the relative positions shown in Fig. 3, and the foot 4 has been fastened to the lower end of the cylinder, the empty cylinder is lowered into place by the aid of the seating tool 6, 7. The cylinder and parts mounted thereon are supported by the head of the seating tool which engages the underside of the internal flange 8.

By lowering the seating tool the empty cylinder may be lowered to the bottom of the well. Ordinarily the friction of the spring 25 upon the internal walls of the cylinder will prevent the cylinder from descending by gravity alone and in such case the parts are forced down by pressing downward on the rod 7 of the seating tool, the head of the seating tool engaging the top of the bottom flange 4^a of the foot 4. When the cylinder has been lowered to place, the seating tool is rotated in such direction as to cause the cylinder to screw downward in the spring dog, said dog being held against rotation by the springs 25 which press against the comparatively rough inner surface of the well casing. In consequence, the dog stands still while the cylinder descends, causing the flange 21 to press down upon the packer 22 and cause the latter to bulge or thicken as illustrated in Fig. 2. This action is continued until the packer forms a very tight joint between the cylinder and the casing, the rubber ordinarily even crowding up somewhat into the space between the perimeter of the flange and the wall of the casing thus preventing the formation of any nook or cranny where sediment may collect. To enhance this effect, it is desirable that the flange 21 be beveled somewhat, as shown in the drawings. When a tight joint has thus been effected, the seating tool is withdrawn from the well and the foot valve 11, 12, 13 is dropped into place. After this the piston is lowered into the cylinder by the rod 19 and all is in readiness for the operation of the pump. If now, it is desired to remove the cylinder, the piston 14 is first lowered onto the foot valve, and rotated so that the threaded boss 15 of the foot valve will be engaged by the plunger 14 and lifted by it out of the well. The seating tool is then lowered into engagement with the foot 4 and rotated in such direction as to cause the pump cylinder 2 to rise relatively to the dog, thus releasing the rubber packer 22 and permitting the latter to contract to normal condition, shown in Fig. 3. Thereupon, by raising the seating tool the cylinder and parts supported thereon may be lifted out of the well. With my construction there is no opportunity for sand or sediment to gather at any point between the well casing and the cylinder. The intermediate space 3 is open at the bottom and in fact the parts make no contact with the well casing except at the extreme upper end of the cylinder, and it will be understood that no sediment can gather above the cylinder for the reason that the water is being actively agitated by every movement of the pump rod. In consequence, as soon as the rubber packer is released, there is nothing to prevent the rise of the cylinder and attached parts, except the friction of the springs 25 which may be 130

readily overcome by exerting comparatively small upward pressure upon the rod 7 of the seating tool.

Having thus described my invention, what I claim as new and desire to secure by Letters Patent, is:—

1. In combination, a tubular pump cylinder externally threaded near the top, an external flange at the top of said cylinder, a spring dog screwing on the outside of said cylinder, and a resilient ring interposed between the upper end of the spring dog and the flange on the pump cylinder.

2. In a pump cylinder, the combination, with the cylinder proper, having an external flange at its upper end, of a spring dog screwing on the outside of said cylinder, and resilient packing material interposed between the upper end of said dog and the flange on the upper end of the cylinder, said flange flaring upwardly and outwardly, substantially as described.

3. In a device of the class described, the combination of a pump cylinder having an external flange at its upper end, a resilient packing ring encircling said cylinder adjacent to said flange, a spring dog screwing on the upper end of said cylinder beneath said packing ring, a seating tool, and means on said cylinder constructed to be engaged and disengaged by said seating tool for rotating said cylinder.

4. In a device of the class described, the combination of a pump cylinder having at its upper end an upwardly and outwardly flaring flange, a resilient packing ring en-

circling said cylinder beneath and adjacent to said flange, a tubular sleeve screwing on the outside of said cylinder adjacent to and beneath said ring, outwardly bulging springs on said sleeve, said springs extending approximately longitudinally and collars formed on said sleeve above and below said springs for protecting them, substantially as described.

5. In a device of the class described, the combination of a tubular well casing, a pump cylinder having an external flange at its upper end, the perimeter of said flange being slightly less than the internal diameter of the well casing, a resilient packing ring surrounding said cylinder beneath and adjacent to the flange thereon, a spring dog screwing on said cylinder beneath and adjacent to said resilient ring, a foot on said cylinder, and a seating tool adapted to engage and disengage said foot for rotating said cylinder and raising and lowering the same.

6. In combination, a tubular pump cylinder having an integral flange flaring upward and outward from the top of the cylinder to thereby produce a wedging action, a resilient ring beneath said flange in contact therewith, and means for crowding upward against the bottom of said ring.

In witness whereof, I have hereunto subscribed my name in the presence of two witnesses.

EDWIN W. CLARK.
